UNITED STATES PATENT OFFICE.

HARRY W. MACDOUGALL, OF EAST ORANGE, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,277,444.

Specification of Letters Patent. Patented Sept. 3, 1918.

Application filed January 2, 1918. Serial No. 209,969.

To all whom it may concern:

Be it known that I, HARRY W. MACDOUGALL, a citizen of the United States, residing at East Orange, in the county of 5 Essex, State of New Jersey, have invented certain new and useful Improvements in Telephone-Exchange Systems, of which the following is a full, clear, concise, and exact description.

10 This invention relates to telephone exchange systems and more particularly to such systems employing trunk circuits extending between two central offices over which connections may be established between telephone lines terminating at the different offices.

An object of this invention is the provision of improved signaling means for systems of this character.

20 In accordance with this invention, a trunk circuit extending from a central office of the central energy type to a central office of the magneto or local battery type, is provided with apparatus for automatically connecting 25 a source of ringing current to the trunk circuit upon connection therewith at the central energy office of a link circuit to cause the operation of a signaling device at the magneto office, which current is then automatically disconnected from the trunk circuit when connection is made therewith at the magneto office.

One embodiment of this invention is illustrated in the accompanying drawing in 35 which a trunk circuit A extends from a central office X of the central energy type to a central office Y of the magneto type. A cord circuit C provided at the central office X may be connected with the trunk circuit 40 A, while a cord circuit D provided at the magneto office may be connected with the other end of the link circuit. All apparatus shown in the left of the dotted line 2, 2 of the drawing is located at the central office

45 X and that shown to the right thereof is located at the magneto office Y. At the central office X the link circuit terminates in a jack 5 located at a local subscriber's position and in a jack 6 located at a toll position.

Assuming that the operator located at the subscriber's position of central office X desires to signal the operator at the magneto office Y, calling plug 7 of the cord circuit C is inserted into the jack 5 of the trunk 55 circuit. Calling supervisory lamp 8 is thereby lighted and relay 9 operated over a circuit from battery through the lamp 8 the winding of relay 9, sleeve contacts of the plug 7 and the jack 5, middle normal contacts of relay 10, contact of relay 18, and normal contacts of relay 11 to ground. 60

Relay 9 in operating causes the operation of ringing relay 12 over a circuit from battery through resistance 13, the winding of 65 relay 12, the normal contact of relay 14, the contact of trip relay 15, and the contact of relay 9 to ground. Ringing relay 12 in operating connects ringing current to the trunk over a circuit from a source of 70 ringing current 16 through the winding of trip relay 15, lower alternate contact of ringing relay 12, ring contacts of the plug 7 and the jack 5, upper normal contact of relay 17, the winding of relay 18, tip contacts of the jack 5 and the plug 7, and the upper alternate contact of ringing relay 12 to ground. Trip relay 15 and relay 18 are immediately operated over this circuit. The operation of the trip relay 15 opens a 75 short circuit about the winding of relay 14 which is thereupon energized to complete a short circuit about the winding of ringing relay 12. Ringing relay 12 thereupon releases, disconnecting ringing current 80 from the trunk. Relay 14 in operating also completes a locking circuit for itself from battery through the resistance 13, alternate contact and winding of relay 14, and the contact of relay 9 to ground. Relay 18 in 85 operating opens its contact, removing a short circuit from the winding of relay 11 which is thereupon operated, opening its normal and closing its alternate contacts.

Relay 11 in operating also causes the operation of relay 17. Relay 17 thereupon opens its normal and closes its alternate contacts, the closure of its upper alternate contact closes a normal break in the ring strand of the trunk circuit and the opening 90 100

of its upper normal contact disconnects relay 18 from across the talking conductors of the trunk circuit. The closure of the lower alternate contact 25 of relay 17, causes 5 the operation of relay 26 over a circuit from battery through the right-hand winding of retardation coil 27, contact 28 of jack 29, upper normal contact of relay 10, winding 43 of repeating coil 38, contact 25 of relay 10, windings of relay 26, winding 44 of repeating coil 38, lower normal contact of relay 10, contact 30 of jack 29, and left-hand winding of retardation coil 27 to ground. Relay 26 in operating opens its 15 normal and closes its alternate contacts, thereby causing the operation of relays 31 and 32 over a circuit from battery through alternate contact 35 of relay 17, alternate contact of relay 26, left-hand contact of relay 36, and the winding of relay 31 and the upper winding of relay 32 in parallel to ground. Relay 31 in operating connects a 20 source of ringing current 37 in circuit with the two windings 40 and 41 of the repeating coil 38. This circuit may be traced from a source of ringing current through the alternate contact 39 of relay 31, the winding 40 of the repeating coil 38, contact of relay 32, the winding 41 of the repeating coil 38, and 25 contact 42 of relay 31 to ground. Current is thereupon induced into windings 43 and 44 of the repeating coil which are in circuit with the winding of a drop 45. The coil of this drop is thereupon energized, attracting 30 its armature and dropping its shutter which furnishes a signal to the operator at the magneto office. Relay 31 in operating as before described opens up the talking circuit of the trunk, completes a locking circuit 35 for itself through its contact 46, and in addition causes the operation of relay 36 over a circuit from battery through contact 35 of relay 17, right-hand winding of relay 36 and contact 48 of relay 31, to ground. 40 Relay 36 in operating opens its left-hand contact which is in the initial energizing circuit of relays 31 and 32, and closes its right-hand contact, thereby establishing a locking circuit for itself. Ringing current 45 from source 37 remains connected with the trunk circuit until the operator at the magneto office answers.

The operator at the magneto office Y observing that the shutter of the drop 45 has 55 fallen, inserts plug 50 of the cord circuit D into the jack 29, thereby opening contacts 30 and 28 and disconnecting from the trunk circuit battery supplied through the windings of the retardation coil 27. Relay 26 60 thereupon releases its armature, opening a contact in the circuit which includes the winding of relay 31 and the upper winding of relay 32. These relays thereupon release their armatures. Relay 31 in releasing dis-

connects ringing current from the trunk circuit and closes the talking circuit thereof. Relay 32, however, is immediately operated again upon the closure of the normal contact of relay 26. The circuit therefor may be traced from battery through contact 35 70 of relay 17, normal contact of relay 26, and the lower winding of relay 32 to ground. Since relay 31 is now deenergized when relay 32 closes its contact, supervisory relay 55 of the cord circuit C operates over a circuit from battery through the winding of supervisory relay 55, lower normal contact of ringing relay 12, ring contacts of the plug 7 and the jack 5, upper alternate contact of the relay 17, lower normal contact of relay 31, winding 40 of the repeating coil 38, contact of relay 32, winding 41 of repeating coil 38, upper normal contact of relay 31, tip contacts of the jack 5 and the plug 7, and upper normal contact of ringing relay 12 to 80 ground. Supervisory relay 55 in operating completes a shunt including resistance coil 13 for the calling supervisory lamp 8, thereby extinguishing the lamp. The extinguishment of this lamp indicates to the originating operator that the operator at the magneto office has answered.

When the operator at the magneto office withdraws the plug 50 from the jack 29, the circuit of relay 26 is established, energizing 95 the relay. The opening of the normal contact of relay 26 causes the deenergization of relay 32 which opens its contact. Supervisory relay 55 is thereby deenergized and the supervisory lamp 8 is lighted to furnish 100 a disconnect signal to the originating operator. The closure of the alternate contact of relay 26 does not cause the reenergization of relays 31 and 32, for the left-hand contact of relay 36 which is in the initial energizing circuit of relays 31 and 32 is now 105 open, relay 36 being locked up. In this way ringing current cannot be connected with the trunk circuit upon the disconnection of the cord circuit D therefrom. The 110 operator at the central office X, upon observing the disconnect signal 8, withdraws the plug 7 from the jack 5, whereupon all apparatus is restored to its normal condition.

The operator at the magneto office Y may signal the operator at the local position or the operator at the toll position of the central office X. To do so the plug 50 of the cord circuit D is first inserted into the jack 120 29 of the trunk circuit A. Wishing to signal the operator at the local position, ringing key 60 is actuated, thereby causing the operation of relays 61 and 36 over a circuit from a source of ringing current 62 through the contact of ringing key 60, ring contacts 125 of the plug 50 and the jack 29, lower normal contact of relay 10, winding 44 of repeating

coil 38, condenser 63, left-hand winding of relay 61, left-hand winding of relay 36, and middle normal contact of relay 17 to ground.

Relay 61 in operating lights the lamp 64 which is associated with the jack 5, and establishes a locking circuit for itself through its right-hand winding, the lamp 64 being lighted and the locking circuit being maintained over a circuit including the left-hand contact of relay 61 and the middle normal contact of relay 17. Relay 36 in operating, closes its right-hand contact, establishing a locking circuit for itself from battery through the right-hand contact of relay 61, right-hand winding and right-hand contact of relay 36 to ground. One reason for operating and locking up relay 36 when relay 61 operates is to open the normal contact of relay 36 so that when the operator inserts plug 7 into jack 5, relay 31 cannot be energized. In this way ringing current cannot be connected with the trunk.

Upon the insertion of the plug 7 into the jack 5, relays 9, 12, 14 and 15 of the cord circuit and relays 18, 11 and 17 of the trunk circuit operate in the manner hereinbefore described. Upon the operation of relay 17, relay 32 is operated over a circuit from battery through the contact 35 of relay 17, normal contact of relay 26, and the lower winding of relay 32 to ground. Relay 32 thereupon closes its contact, establishing an energizing circuit for the supervisory relay 55 which attracts its armature to extinguish the supervisory lamp 8. Relay 17 in operating also opens the locking circuit of relay 61 which releases and extinguishes the lamp 64. Relay 36, however, remains locked up until the release of relay 17 upon the subsequent removal of the plug 7 from the jack 5, for battery to the right hand winding of relay 36 is furnished through contact 35 of relay 17.

Should the operator at the magneto office desire to signal the toll operator, ringing key 70 instead of 60 is actuated to connect a source of ringing current 71 with the trunk circuit, thereby causing the operation of relays 72 and 36 over a circuit from the source of ringing current 71, through the contact of ringing key 70, tip contacts of the plug 50 and the jack 29, upper normal contact of relay 10, winding 43 of the repeating coil 38, condenser 73, right-hand winding of relay 72, left-hand winding of relay 36, and the middle normal contact of relay 17 to ground. Relay 72 in operating establishes a locking circuit for itself from battery through the lower normal contact of relay 17, left-hand contact and left-hand winding of relay 72 to ground. The lamp 74 associated with the jack 6 is in parallel with the left-hand winding of relay 72 and is lighted when this locking circuit is completed. The

closure of the right-hand contact of relay 65 72 completes a locking circuit through the right-hand winding of relay 36. The toll operator upon observing the lighted condition of the lamp 74 inserts into the jack 6 the plug of a cord circuit, the sleeve strand 70 of which is connected with battery, thereby causing the operation of relay 10.

Relay 10 in operating causes the energization of relay 11 over a circuit from battery through the alternate contact of relay 10, 75 and winding of relay 11 to ground. Relay 11 thereupon causes the operation of relay 17 to extinguish the lamp 74 and release the relays 72. Relay 36 remains locked up until the toll operator disconnects the plug from the jack 6. Relay 10 in operating also opens up contacts in the talking conductors of the trunk circuit, thereby disconnecting the local position end of the trunk to prevent any interference from a local operator. It will also 85 be observed that the closure of the alternate contact of relay 10 connects a busy test potential to the local jack.

What is claimed is:

1. A telephone exchange system comprising a trunk circuit extending from a first to a second switchboard, a source of ringing current, a link circuit at the first switchboard, means in the trunk circuit responsive to the connection of the link circuit with the trunk circuit to connect therewith the source of ringing current, a signaling device at the second switchboard operated by current from said source, a switching device at the second switchboard, and means responsive to the actuation of the switching device for disconnecting the source of ringing current from the trunk circuit. 90 95 100

2. A telephone exchange system comprising a trunk circuit extending from a first to a second switchboard, a source of ringing current, a link circuit at the first switchboard, a relay in the trunk circuit operating when the link circuit is connected therewith to connect the source of ringing current with the trunk circuit, a signaling device at the second switchboard operated by current from said source, switching mechanism at the second switchboard, and means responsive to the operation of the switching mechanism for disconnecting the source of ringing current from the trunk circuit. 105 110 115

3. A telephone exchange system comprising a trunk circuit extending from a first to a second switchboard, a source of ringing current, a link circuit at the first switchboard, an electromagnetic switching device in the trunk circuit actuated when the link circuit is connected therewith to connect the source of ringing current with the trunk circuit, a signaling device at the second switchboard operated by current from said source, a link circuit at the second switch- 120 125

board, and means responsive to the connection thereof with the trunk circuit for disconnecting the source of ringing current therefrom.

5. A telephone exchange system comprising a trunk circuit extending from a first to a second switchboard, a source of ringing current, a link circuit at the first switchboard, an electromagnetic switching device 10 in the trunk circuit actuated when the link circuit is connected therewith to connect the source of ringing current with the trunk circuit, a signaling device at the second switchboard connected with the trunk circuit and operated by current from said source, a link circuit at the second switchboard, and means responsive to the connection thereof with the trunk circuit for disconnecting the signaling device and the 20 source of ringing current therefrom.

5. A telephone exchange system comprising a trunk circuit extending from a first to a second switchboard, a source of ringing current and a link circuit at the first switchboard, a relay in the trunk circuit energized when the link circuit is connected with the trunk circuit to connect therewith the source of ringing current, a signaling device at the second switchboard connected 25 with the trunk circuit and operated by current from said source, a link circuit at the second switchboard, and switching mechanism actuated upon the connection of the link circuit with the trunk circuit for disconnecting the signaling device and the 35 source of ringing current therefrom.

6. A telephone exchange system comprising a trunk circuit extending from a first to a second switchboard, a source of ringing 40 current and a link circuit at the first switchboard, switching means responsive to the connection of the link circuit with the trunk circuit, a source of direct current and a signaling device at the second switchboard, and an electromagnetic switching device 45 actuated by current from the direct current source upon the response of the switching means to connect the source of ringing current with the trunk circuit for operating the 50 signaling device.

7. A telephone exchange system comprising a trunk circuit extending from a first to a second switchboard, a source of ringing current and a link circuit at the first switchboard, a relay responsive to the connection of the link circuit with the trunk circuit, a source of direct current and a signaling device at the second switchboard, and electromagnetic means actuated by current 55 from the direct current source upon the response of the relay for connecting the source of ringing current with the trunk circuit for operating the signaling device.

8. A telephone exchange system comprising 60 a trunk circuit extending from a first

to a second switchboard, a source of ringing current and a link circuit at the first switchboard, a relay energized upon the connection of the link circuit with the trunk circuit, a source of direct current and a signaling device at the second switchboard, a second relay responsive to current from the direct current source when the first relay is energized, and a third relay actuated upon the response of the second relay to connect 70 the source of ringing current with the trunk circuit for operating the signaling device.

9. A telephone exchange system comprising a trunk circuit extending from a first to a second switchboard, a source of ringing 80 current and a link circuit at the first switchboard, a relay in the trunk circuit energized upon connection of the link circuit therewith, a source of direct current and a signaling device at the second switchboard, a second relay responsive to current from the direct current source when the first relay is energized, a third relay actuated upon the response of the second relay when the first relay is energized to connect the source of 85 ringing current with the trunk circuit for operating the signaling device, an operator-controlled switching device at the second switchboard, and means in the trunk circuit responsive to the actuation of the switching device for disconnecting the source of ringing current from the trunk circuit.

10. A telephone exchange system comprising a trunk circuit extending from a first to a second switchboard, a source of ringing 100 current in the link circuit at the first switchboard, a relay in the trunk circuit energized upon connection of the link circuit therewith, a source of direct current at the second switchboard, a signaling device thereat 105 connected with the trunk circuit, a second relay responsive to current from the direct current source when the first relay is energized, a third relay actuated upon the response of the second relay when the first is energized to connect the source of ringing current with the trunk circuit for operating the signaling device, a link circuit at the second switchboard, and means responsive to the connection of the link circuit with 110 the trunk circuit for disconnecting the signaling device and the source of ringing current therefrom.

11. A telephone exchange system comprising a trunk circuit extending from the first to a second switchboard, a source of ringing current and a link circuit at the first switchboard, a relay in the trunk circuit energized upon connection of the link circuit therewith, a source of direct current and a signaling device at the second switchboard, a second relay responsive to current from the direct current source when the first relay is energized, a third relay energized upon the response of the second relay while the first 120

relay is energized to connect the source of ringing current with the telephone circuit for operating the signaling device, a locking circuit for the third relay established 5 upon the energization thereof, a fourth relay responsive to the energization of the third relay to open the initial energizing circuit of the third relay, a link circuit at the second switchboard, and means respon-

sive to the connection thereof with the trunk 10 circuit for causing the opening of the locking circuit of the third relay, thereby to disconnect the source of ringing current from the trunk circuit.

In witness whereof, I hereunto subscribe 15 my name this 28th day of December A. D., 1917.

HARRY W. MACDOUGALL.
